atty.

UNITED STATES PATENT OFFICE.

GEORGE G. BAYNE, OF QUINCY, AND FRED A. RUNKLE, OF MACOMB, ILLINOIS.

ROAD-DRAG.

1,214,121.

Specification of Letters Patent. Patented Jan. 30, 1917.

Application filed April 29, 1916. Serial No. 94,394.

To all whom it may concern:

Be it known that we, GEORGE G. BAYNE and FRED A. RUNKLE, citizens of the United States, whose post-office addresses are respectively, Quincy, Adams county, Illinois, and Macomb, McDonough county, Illinois, have jointly invented a new and useful Road-Drag, of which the following is a specification.

10 Our invention relates to implements for dragging, smoothing, grading and surfacing roads; and the principal object of the invention is to generally simplify the construction and increase the utility and efficiency of devices of this character.

In the accompanying drawings: Figure 1 is a top plan of the form of drag preferred by us; Fig. 2, a section in the line 2-2 in Fig. 1; and Fig. 3, a vertical, longitudinal

20 section, taken in the line 3-3 in Fig. 1.

In the different views like parts are designated by the same reference characters.

25 4 designates the usual coupling-link and 5 a draft-chain the respective ends of which engage rings 6 which engage side frame-bars 7 which are pivotally connected by deck-boards 8. The rear ends of the bars 7 are pivotally connected with brackets 30 which are fixed one to and near each outer 30 end of the plane 11 and one at its midlength.

18 designates a cutting-plane and 20 denotes a bracket with which it is pivotally connected.

35 31 designates a knuckle provided with a vertically arranged aperture for the engagement of a king-pin 32, and with a horizontally arranged eye 33 in which the rock-bar 20 is mounted.

34 indicates a rocker-casting having eyes 40 35 registering with the eye 33 and receiving the rod 20. To said casting 34 is suitably fixed the front blade or plane 18. Secured at 36^a to the central frame bar 7" is a lever 36 the fore end of which overlies the sector 45 39 and has an aperture adapted to register with any of a series of openings 38 in said sector. 40 indicates a lock-pin. Connected at 41 to the head of the rocker-casting 34 is the front end of a link 42 the rear end of 50 which is pivotally connected by a pin 42' with a blade-rocking lever 48 which is fulcrumed in eyes 43 projecting from a casting 50.

44, 44 designate brackets projecting from

the casting 50 provided with corresponding 55 slots 45 adapted for the passage of a lock-pin 46 which is adapted for engagements with the series of openings 47 in said link. The plate is pivotally connected at its front end with the pin 32 and at its rear end riveted to the sector 39.

Fixed to the middle plate 8 are the ends of a sector 51 provided with a series of openings 52 each of which is adapted for engagement by a pin 53 which passes first 65 through the lever 36. The middle knuckle 30 has an eye for the passage of a pivot-bolt 54.

55 indicates a truss-plate the front end of which is pivotally connected with the pin 70 32 and the rear end similarly connected with the pin 54.

56 and 57 are retaining pins.

It will be noticed that the eye 4 may engage the links 5 either midlength of the 75 chain or to one side thereof, as desired, to incline the drag members with reference to the direction of travel. The smoothing plane is stationary, and acts as a trowel or smoothing-plane. The front plane may be 80 actuated by the lever 48 to rock it on its longitudinal axis whereby it may be made to stand vertically or inclined either forward or back.

The members 8, 11 and 18 are maintained 85 constantly in parallelism, and this is true also of the members 7', 7", 7", 36 and 55. While the sector 30 is concentric with, and the sector 51 eccentric to the center 32, the lever 36 is operatively connected with both 90 95 of said sectors. The double-sector with which is operatively connected a single operating lever provides for extreme rigidity of the entire drag. Any desired lateral adjustment within limits may be made by withdrawing the pins 40 and 53 and moving the lever 36 laterally.

The curved contact-face 11' of the trowel or smoothing plane 11 works especially well on moist or even muddy roads, for it acts 100 as a trowel or smoother, gliding along and leaving a smooth, even surface. When working roads or grounds which are moist or wet, better results will be attained by inclining the lower edge of the blade or plane 105 18 rearward, so that it also acts as a drag, but when working very dry soils the blade 18 is preferably inclined in the opposite di-

rection. It will be evident that the device is equally as well adapted for field as for road work.

Having thus described our invention we claim as new the following, to-wit:

1. In a drag, a front plane, a rock-shaft on which it is mounted, a sector connected with the rock-shaft, a drag-frame pivotally connected at its front end to said plane, 10 means for rocking said plane on said shaft, a plane at the rear end of the frame, a lever for swinging said frame in a horizontal arc relatively to the front plane, and means associated with said sector and lever for locking 15 said frame from swinging.

2. In a drag, a front plane, a rock-shaft on which it is mounted, a sector connected with the rock-shaft, a drag-frame pivotally connected at its front end to said plane, 20 means for rocking said plane on said shaft, a plane at the rear end of the frame, a sector fixed on the frame, eccentric to the one recited, a lever adapted to swing the frame and rear plane in a horizontal arc, and plural means whereby said lever may be locked 25 in engagement with both sectors.

3. In a drag, a knuckle, a rocker-casting pivoted thereto to rock in a vertical arc, a plane fixed to said casting, a drag frame 30 pivotally connected to said knuckle to swing in a horizontal plane, means for rocking said casting, means for locking it in set position,

means for swinging the frame in the arc recited, means for locking it in set position, and a plane arranged at the rear part of the 35 frame.

4. In a drag, a knuckle, a rocker-casting pivoted thereto to rock in a vertical arc, a plane fixed to said casting, a drag frame pivotally connected to said knuckle to swing 40 in a horizontal plane, a link one end of which is attached to said casting, a lever for moving said link forward or back, means for locking the lever in set position, means for swinging the frame in the arc recited, 45 means for locking it in set position, and a plane arranged at the rear part of the machine.

5. In a drag, a front plane, a rock-shaft on which it is mounted, a sector connected 50 with the rock-shaft, a drag-frame pivotally connected at its front end to said plane, a link for rocking said plane on said shaft, a lever for imparting reciprocating movements to said link, a plane at the rear end 55 of the frame, a lever for swinging said frame in a horizontal arc relatively to the front plane, and means associated with said sector and the last recited lever for locking said frame from swinging.

In witness whereof we hereunto set our hands this 1st day of April, 1916.

GEORGE G. BAYNE.
FRED A. RUNKLE.
